6 Claims. (Cl. 241—197)

1

This invention relates to impact bars for impeller breakers which exert an impact action in the breaking of rocks, ores, and similar hard materials. It has particular pertinency to double-impeller breakers which exert a so-called dual impact action.

Double-impeller breakers exerting such dual impact action are a comparatively recent development in the field of crushers and similar machines for breaking rocks, ores, and similar hard materials into pieces of desired size for industrial uses. These breakers represent a radical departure from conventional crushers, rolls, and similar machines.

The term "dual impact action" has reference to the manner in which the double impellers of the machine operate in conjunction with stationary breaker bars, so that raw material fed to the machine receives a first breaking impact from the impellers, and then a second breaking impact as it is forcibly flung against the stationary breaker bars by the impact action of the impellers. Thus, breaking of the material is accomplished entirely by impact action, as distinguished from conventional crushing action.

In a machine of this type, the two impellers rotate in opposite directions opposed to the feed of material, so that material falling between them is forcibly ejected outwardly in the direction of the stationary breaker bars. A gravity feed is commonly utilized, with the material falling between the two impellers, which are horizontally disposed. Immediately afterwards, the material is ejected upwardly and outwardly against the stationary breaker bars, which are horizontally positioned above the rotating impellers in spaced parallel relationship therewith.

The impellers, as commonly supplied, each comprise an elongate center-body of uniform cross-section throughout, mounted on a shaft suitably journaled for rotation. The cross-sectional configuration of the center-body may be appropriately described as approximately equilaterally triangular, with the sides of the triangle convexly arcuate.

The longitudinally-extending vertices of the center-body are re-entrantly recessed to provide elongate locking slots, into which are slid, endwise, respective elongate impact bars of approximately I-configuration in cross-section. One of the longitudinally extending cross-flanges and the web of the I-bar fit into the locking slot, the remaining cross-flange protruding outwardly and longitudinally of the center-body, at a vertex thereof, as an impeller impact member. End wedges lock the respective impact bars in place

2

against longitudinal movement, and cinch them tightly in the locking slots against play radially of the center-body. Thus, the impact bars are rigid with respect to the center-body. The two cross-flanges of each I-bar are extremely heavy, and have well-defined corner edges for impact purposes, only one edge being in working position at any given time.

In operation, the leading edge portions of the 10 respective impact bars exert an upward striking action upon material that is fed from above into the troughed space between the impellers. This impact action serves to intercept the incoming material and to project the same upwardly so 15 as to strike the heavy stationary breaker bars. Such striking action of the impact bars rapidly wears away those respective corner edges thereof which lead in the rotation of the impellers.

It is a much-publicized feature of this double- 20 impeller breaker that the I-shaped impact bars of the impellers may be removed from the center-body, turned, and reinserted when a particular striking edge thereof becomes worn away or is otherwise rendered unfit for further use. Ordinarily there are four striking edges on each impeller bar, these edges being used successively. Thus, three replacements for the original striking edge are provided by each bar. When, however, all four longitudinally-extending corner edges of an impact bar have gone through a 25 working position and been sufficiently worn, the bar must be completely discarded and replaced by a new one.

Each impact bar of what is known as the 30 model 30-30 Double Impeller Breaker manufactured by the New Holland Manufacturing Co. of Mountville, Pennsylvania, which is a typical machine of average size, weighs approximately 400 pounds, and, although removal and reversal or 35 replacement of same ordinarily consumes but one-half hour of time, the total time lost from productive work in the reversal or replacement of the six impact bars incorporated in the two impellers, amounts to 3 hours. Furthermore, the 40 labor of two men is required for the handling of each bar. Where the material worked upon is very hard and abrasive, as in the case of ores to be reduced in size for use in the metallurgical industry, it has been found that each striking edge of an impact I-bar lasts only approximately 45 72 hours, meaning a shutdown for a period of 3 hours twice a week where a plant is operating 24 hours a day. This is prohibitive in most industries, even though great advantages are derived 50 from use of this type breaker as compared with 55 more conventional types.

Furthermore, heavy losses are sustained in the continual junking of worn impact bars. The discarded bars represent tons of expensive material, the junking of which is highly uneconomic. Again, in instances of unduly abrasive materials it is necessary that the impact I-bars be made of such hard metal that serious difficulty is encountered by cracking of the web of the I under impact on the working flange thereof. Thus, the use of the machine can be justified only in exceptional instances, or in industries where the rock materials handled are of such character as to produce only minor wear of the impact surfaces.

Faced with such problems in the use of this double-impeller, dual-impact-action breaker, we have perfected a composite impact bar which overcomes the difficulties to such an extent as to render this type of breaker economically applicable to practically all industries utilizing crushed ore, rock, and other hard, tough, and abrasive materials, almost regardless of the degree of hardness, toughness or abrasiveness of the material.

Accordingly, principal objects of the invention are:

To provide an impact bar for double-impeller, dual-impact-action breakers which has superior wear and impact resistant qualities, and which, at the same time, permits of rapid removal and replacement of wear surfaces thereof as and when required, with a minimum of discard.

To provide a composite impact bar permitting rapid replacement of wear surfaces without removal of the entire bar from the center-body, and enabling the use of different materials for different parts of the impact bar in accordance with the various properties required by the respective parts.

To provide for rigid securement of all parts of the composite impact bar with respect to the center-body, while affording rapid release of impact parts from other parts thereof and from the center-body.

To provide the improved impact bar in such manner that no changes need be made in either the machine proper nor in the center-bodies of the respective impellers, to accommodate such bars.

To provide the above by means of a simple and economical arrangement which adds to the overall efficiency of the machine.

We achieve these objects by a construction embodying a permanent core or skeleton bar of reduced cross-section, adapted to be inserted within and extend longitudinally of a locking recess of the center-body in substantially the same manner as the I-bars presently in use. Such core or skeleton bar need not be, however, and preferably isn't symmetrically formed, for it is not turned or reversed in the replacement of wear surfaces. That longitudinally-extending portion thereof which projects from the recess when such core or skeleton bar is installed in the center-body, is formed to receive and retain a removable and replaceable wear and impact cap arrangement which contains but a small fraction of the metal content of the entire bar and which may be conveniently and quickly installed and removed with respect to the core or skeleton bar. In this manner, not only is time, labor, and material saved in the replacement of worn striking edges, but the cap-supporting core may be made of a tough material especially adapted to absorb impact without cracking, while the cap may be of a hard and abrasive-resistant material selected

for the particular operation, being dependent in quality upon the nature of the raw material to be broken by the machine.

The particular construction presently preferred involves the making of the permanent core of a bar formation which differs significantly from that previously utilized, in that it is not symmetrical. A longitudinally-extending foot portion is dimensioned to be received by the locking slot of the center-body, and may be reduced in bulk as found appropriate in order to save material. At the top of the bar, a longitudinally-extending cross-flange portion is reduced in dimension such that it serves as a tongue adapted to receive a mating groove of the wear and impact cap arrangement. In this manner, the permanent core bar and the cap arrangement may be both securely locked in position in the center-body by means of wedges, enabling rapid removal and replacement of the cap arrangement with respect to the core bar.

We have found it highly advantageous in practice to make the cap arrangement in sections, considered longitudinally of the core bar, the several sections being successively slid into place on the core bar which supports them in common. Ordinarily, three cap sections will be utilized for a single core bar, the cap sections being individually fastened to the core bar by means of removable pins or plugs which fit into receiving passages formed through a wear-protected portion of the cap section and having continuations formed in the core bar. A pair of locking wedges, drawn into place by means of a mutually interconnecting tie rod, is utilized in much the same manner as in the conventional construction to complete the fastening arrangement. Such wedges, however, are here formed to react against both the respective terminal cap sections and the base flange of the permanent core, effectively locking both the cap arrangement and the permanent core in working position in the center-body of the impeller.

In changing worn caps, the wedges and pins are removed, and the individual cap sections slipped off the receiving flange-tongue of the core bar. Since each cap section has two impact edges, one reversal is possible prior to replacement by a new cap section.

It should be noted that, in this preferred construction, the locking wedges exert pressure longitudinally of the cap arrangement, which results in the binding of the transversely extending fastening pins in their receiving passages and the production of an especially effective lock of shoes to core bar and core bar to center-body.

While this presently preferred construction has many characteristics which produce superior results in practice, other arrangements of caps and fastening means conforming to the broad inventive concept will be found to be far superior to the conventional impact bars in common use.

Further objects and features of the invention will become apparent from the following detailed description of the presently preferred specific construction illustrated in the accompanying drawings.

In the drawings:

Fig. 1 represents a side elevation, partly in vertical section, of a double impeller, dual-impact-action breaker having impellers embodying composite impact bars pursuant to the invention;

Fig. 2, a fragmentary end-elevation of one of

the impellers, showing one of the composite impact bars securely mounted in the center-body of the impeller, the view being drawn to an enlarged scale;

Fig. 3, a partial elevation and partial section taken largely on the line 3—3 of Fig. 2;

Fig. 4, a partial top plan and horizontal section taken largely on the line 4—4 of Fig. 2;

Fig. 5, a side elevation of the composite impact bar per se, showing the pins utilized to fasten the individual cap sections to the core bar;

Fig. 6, a vertical, transverse section taken on the line 6—6 of Fig. 5;

Fig. 7, a fragmentary perspective view, drawn to an enlarged scale, of an end of a center-body showing a wedge-receiving recess thereof;

Fig. 8, a perspective view of one of the locking wedges which fit into the wedge-receiving recesses; and

Fig. 9, a similar perspective view but showing the opposite side of the wedge.

Referring to the drawings: the double-impeller, dual-impact-action breaker illustrated in Fig. 1 is the aforementioned model 30—30, manufactured by the New Holland Manufacturing Company of Mountville, Pennsylvania. It includes an external housing 10, within which and at a low level thereof are mounted respective impellers 11 on horizontal axes of rotation.

Such impellers each comprise a center-body 12, whose cross section is of equilateral triangular configuration, the sides of the triangle being convexly arcuate. While this particular configuration was adopted by the manufacturer as most desirable in instances where three impact bars are employed, other configurations are possible. The important thing is that the center-body be correctly designed from an engineering standpoint to withstand the stresses and strains imposed upon it during rotation, to provide for maximum effectiveness of the impact bars in operation of the machine, and to provide proper anchorage for the removable impact bars.

The center-body 12 is of uniform cross-section throughout its length, and is fixed to a shaft 13 whose ends are journaled in respective bearings 14 disposed exteriorly of the housing 10.

The two impellers 11 are mounted side by side for rotation in respectively opposite directions, as indicated by arrows in Fig. 1. Their impact action is exerted upwardly against raw material 15 fed from above into the troughed space defined between the two impellers. The material 15 is fed along a table 16 to a point of discharge above the impellers, as illustrated.

In operation, the material 15 receives a first impact action from the upwardly and outwardly rotating impellers 11, and is flung against stationary breaker bars 17, which form, in effect, a cage about the impellers. Such breaker bars 17 extend parallel to the impeller axes, and exert a second impact action on the material flung against them by the impellers.

The invention is not concerned with the structure thus far described, except insofar as it provides a setting for the composite impact bars about to be described. Certain aspects of the impeller center-bodies, as hereinafter set forth, are, however, important in combination with the impact bars of the invention and the particular fastening means here shown.

The center-bodies 12 carry impact bars which directly strike the incoming raw material and

exert a breaking action thereon. As aforementioned, such impact bars as conventionally constructed are of an integral I-configuration possessing four striking edges, the bars being removable and replaceable within respective receiving recesses formed longitudinally and in spaced relationship along the center-body, being placed at and along the respective vertices in those instances where the center-body is triangularly-formed. This arrangement enables the impact bars to be changed in position with respect to the center-body as wear dulls the striking edges thereof, so that the four striking edges of each bar may be successively placed in working position during the course of operation of the machine, and so that the bars may be replaced after all four striking edges are sufficiently worn.

In accordance with the invention, however, the impact bars are of composite formation, embodying a permanent core or skeleton bar and a removable and replaceable wear and impact cap arrangement having two striking edges.

As illustrated, it is presently preferred to make the core or skeleton bar 20 of each composite impact bar of what may be regarded as a conventionalized T-formation in crosssection having an upper longitudinally-extending cross-flange 20a formed as a tongue for receiving the cap arrangement, a lower longitudinally-extending foot 20b for positioning within a locking groove of a center-body 12, and an intermediate longitudinally-extending web 20c. Such core bar 20 possesses only a fraction of the bulk of the impact I-bar commonly employed in this machine, and is a permanent though removable part of the impeller. It is not subject to wear, for it is shielded by the cap arrangement about to be described. Accordingly, it may and preferably is formed of a tough and relatively elastic material, such as a mild low-carbon and high tensile strength steel, capable of absorbing impact shocks without cracking, even though such material would be unsuitable as a direct impact surface.

The cap arrangement preferably comprises a series of individual cap sections 21, longitudinally disposed with respect to the core bar. Each cap section 21 is formed with a groove 22 extending longitudinally of its under-surface and arranged to receive the cross or tongue flange 20a of the core bar in a snug sliding fit. In the present instance there are three individual cap sections 21 for each core bar 20, the sections extending longitudinally of the core bar in end-to-end abutting alignment so as to completely sheath those portions of the core bar which project from the center-body. Since the groove 22 is re-entrant within the cap sections 21, respective portions 21a which define the mouth of the groove longitudinally of the section hug the undersurface of the cross or tongue flange 20a of the core bar and close about the upper portion of the web 20c thereof. The cap sections 21 are installed on the core bar 20 by successively sliding them endwise upon the receiving cross or tongue flange 20a, which serves as the cap attachment portion of the core bar.

For the purposes of securement, transverse pin-receiving passages 23, Figs. 5 and 6, are provided in the under-portions 21a of the respective cap sections, and registering continuations 23—1 are provided in the cross or tongue flange 20a of the core bar. Dowel pins 24 are fitted into the

respective passages 23, 23—1 following placement of the cap sections on the core bar.

It should be noted that each cap section 21 has two oppositely-positioned striking edges, indicated 21b respectively, extending longitudinally thereof, and that the sections may be reversed in position upon the anchoring core bar 20, so that such striking edges are successively disposed in working position on the impeller.

It is a feature of the invention that the composite core bars may be constructed for utilization with impeller center-bodies currently in use.

Such center-bodies, as here shown of triangular formation in cross-section, have re-entrantly formed locking grooves 25 extending longitudinally thereof at the respective vertices. The longitudinally-extending feet of the respective composite impact bars 20 are formed to be slideable endwise into such grooves 25, possessing beveled shoulders 20d which mate with oppositely-disposed, re-entrant, beveled shoulders 25a of such grooves, see Fig. 2. The several cap sections 21 have their under-portions 21a beveled downwardly along the outer faces thereof to mate with bevels 25b which define an elongate flaring mouth for the grooves 25. As so formed, wedges, such for example as those here illustrated and indicated 26, may be utilized in connection with the standard wedge-receiving recesses 27, Fig. 7, formed at opposite ends of each groove 25 of the center-body, such wedges serving in the case of the present invention to retain both the core bar 20 and the several cap sections 21 tightly in place.

The wedges 26 are uniquely formed. As illustrated in Figs. 8 and 9, and having reference to the particular placement shown in Figs. 2 and 3, an upper bevel face 26a is arranged for face-to-face engagement with the bevel face of a corresponding one of the under-portions 21a of a terminal cap section 21 as a pressure guide when the wedge is inserted within a receiving recess 27 of the center-body 12, see Figs. 2 and 3. A corresponding lower wedge-action face 26b is arranged for face-to-face engagement with the bottom wall surface 27a of the recess 27, it being noted that such bottom slopes upwardly and inwardly from the open end of the recess, see Fig. 7, and that the wedge-action face 26b slopes accordingly with respect to the upper bevel face 26a of the wedge. The lateral face 26c of the wedge which adjoins the lower edge of the bevel face 26a is arranged to be parallel with the opposing lateral face of web 20c when the wedge is inserted within a recess 27, see Fig. 2, such opposing lateral faces playing no part in the wedging action. The opposite lateral wedge-action face 26d of the wedge, however, slopes inwardly for face-to-face engagement with the correspondingly sloping lateral wall surface 27b of the recess 27. Thus, the wedge 26 has sloping wedge-action faces bearing against both the bottom and the lateral side wall surfaces, respectively, which define the recess 27, and a guide face bearing against the beveled lower surface of a corresponding one of the under-portions 21a of a terminal cap section 21.

It should be noted that the wedge-action face 26b of the wedge, which engages the bottom wall surface 27a of the recess, also has a certain bearing against the corresponding beveled shoulder portion of the longitudinally-extending foot 20b of the core bar 20, as a lower pressure guide working in conjunction with the above-described upper pressure guide provided in connection with

the terminal cap section 21. Thus, opposing radial locking pressures are brought to bear against the terminal cap section 21 and the corresponding end of the core bar 20, by the wedge 26, thereby effectively holding the entire cap arrangement, and the core bar on which it is carried, against play radially of the impeller. At the same time, longitudinal pressure is exerted by the wedge, tending to bind the dowel pins 24 of the respective cap sections within their receiving passages, and thereby effecting further securing of the cap arrangement with respect to the core bar, as well as a locking action on both cap arrangement and core bar against movement longitudinally of the impeller.

A beveled face 26e is provided for the wedge at what would otherwise be a sharp corner, thereby maintaining all parts of the wedge within the protective coverage of the receiving recess 27.

Pairs of oppositely-placed wedges 26 are drawn into locking positions within their respective recesses 27 by means of respective inter-connecting tie-rods 28, see Fig. 3.

In operation, the core bars 20 and cap sections 21 are held firmly in position by means of the wedges 26, effectively resisting the heavy stresses and strains brought to bear against them by reason of the impact action which they exert against the relatively large pieces of hard material 15.

When the leading one of the two longitudinally-extending striking edges 21b of a cap arrangement is sufficiently worn to be ineffective for its intended purpose, the wedges 26 are removed by unscrewing a cinching nut 29 from the end of the tie rod 28 and removing such tie rod. The dowel pins 24 are removed, and the several cap sections 21 are removed from the cross or tongue flange 20a of the core bar 20, and are reversed in position, end-for-end, being replaced on such tongue flange of the core bar with the opposite and unworn striking edges 21b thereof in leading position. Thereupon, the dowel pins 24, locking wedges 26, tie rod 28, and cinching nut 29 are replaced, and the machine operated again until the newly-positioned striking edge 21b of the cap arrangement is sufficiently worn. Whereupon, a similar procedure is gone through for the installation of new cap sections.

At no time need the core bar 20 be removed from the locking slot 25 of the center-body during the changing of caps, though it is freely removable if for any reason that becomes desirable. The individual cap sections are not unwieldy, and may be easily handled by one workman. The time required for change of caps is only a fraction of that required for the change of the I-bar as previously constructed, and the material lost to scrap is only a fraction of that previously lost. Furthermore, when certain portions of a cap arrangement are subjected to greater wear than other portions thereof, as often happens in practice where the incoming stream of raw material to be broken differs in character transversely of the stream, only those particular cap sections of such cap arrangement which actually need reversal or replacement need be reversed or replaced, whereby waste and maintenance costs are reduced to a minimum.

In order to facilitate the removal of dowel pins 24, their outer ends are advantageously drilled and tapped, as shown at 30, Fig. 6, for receiving the threaded end of a suitable disengaging tool. Furthermore, in order to facilitate

the removal of wedges 26, they are provided with openings 31, Fig. 9, for anchoring a suitable wedge-pulling tool.

The tie rod 28 connecting a pair of oppositely positioned wedges 26 extends through passages 32, Figs. 8 and 9, formed in the respective wedges, and through a passage 33, Fig. 7, formed in and extending longitudinally of the corresponding overhanging lip defining the mouth of re-entrant locking groove 25 of the center-body. Such passages 32 and 33 are approximately oval in configuration, so as to afford limited lateral travel for the tie-rod 28 as the wedges travel inwardly of the recesses 27 during the cinching operation.

It has been convenient to illustrate and describe important features and characteristics of the invention from the standpoint of impellers employed in a particular type of impeller breaker, namely, the double-impeller dual impact action breaker manufactured by the New Holland Manufacturing Co., as aforesaid. Nevertheless, it is obvious that impact bars of the invention may be utilized in connection with suitable impellers of other types of breakers, whether utilizing a single impeller in connection with other co-operating mechanism or double impellers as here illustrated.

Though this invention is here illustrated and described in detail with respect to one presently preferred form thereof, it should be understood that changes may be made therein and that other forms may be constructed on the basis of the teachings hereof, by those skilled in the art, without departing from the protective scope of the claims which here follow.

We claim:

1. A composite impact bar assembly for impeller breakers having a center-body provided with at least one re-entrant and longitudinally extending locking groove, and wedge-receiving recesses at opposite ends of said groove, said assembly comprising an elongate core bar having longitudinally-extending foot, cap-attachment portion, and intermediate web, said foot being shouldered longitudinally with respect to the web for securing within said re-entrant locking groove of said impeller center-body, and said cap-attachment portion being formed as a cross flange arranged to project outwardly from said locking groove as an attachment tongue for a cap arrangement when said bar is installed in the center-body; a wear and impact cap arrangement comprising a plurality of individual cap sections adapted to fit together in end-to-end longitudinal alignment, the several cap sections having their undersurfaces correspondingly re-entrantly grooved for snug mating with the attachment tongue of the core bar; and fastening means for securing the cap arrangement to the core bar, said means including a pair of wedges for insertion in respective ones of said wedge-receiving recesses, said wedges being formed for reaction against said foot, the terminal sections of said cap arrangement, and the center-body and means for forcing said wedges inwardly of said recesses.

2. An impeller for impeller-type breakers, comprising an elongate center-body of substantially uniform cross-section throughout its length; a plurality of re-entrant locking grooves extending, respectively, longitudinally from end-to-end of the center-body in mutually spaced relationship about the peripheral surface thereof; wedge-receiving recesses formed at opposite ends of the center-body adjacent and opening into respective locking grooves thereof; a plurality of elong-

gate core bars having respective elongate feet and webs fitted into respective locking grooves of the center-body in substantially mating relationship therewith, said core bars having, further, respective elongate cross-flanges serving as cap-attachment tongues projecting from said locking grooves; sets of longitudinally-aligned wear and impact resisting cap sections having re-entrant grooves along their undersurfaces snugly mating with the tongues of respective core bars; locking wedges fitted into respective recesses of the center-body, said wedges being formed for and having reaction against corresponding feet of the core bars, corresponding terminal cap sections, and walls of corresponding recesses of the center-body; and means cinching pairs of opposing wedges tightly into place.

3. The combination recited in claim 2, wherein each cap section has a pin-receiving passage extending transversely through an underpart thereof, and the tongue of each core bar is provided with aligned continuations of the passages of the cap sections which are mounted thereon; and wherein dowel pins are snugly fitted within respective passages and the continuations thereof.

4. The combination recited in claim 2, wherein the cinching means comprise tie rods equipped with cinching nuts.

5. A composite impact bar assembly for impeller breakers having a center-body provided with at least one re-entrant and longitudinally extending locking groove, and wedge receiving recesses at opposite ends of said groove, said assembly comprising an elongate core bar having a longitudinally-extending foot, cap-attachment portion, and intermediate web, said foot being shouldered longitudinally with respect to the web for securing within said re-entrant locking groove of said impeller center-body, and said cap-attachment portion being formed as a cross flange arranged to project outwardly from said locking groove as an attachment tongue for a cap arrangement when said bar is installed in the center-body; a wear and impact resistant cap arrangement having its undersurface re-entrantly grooved in correspondence with and for snug mating with the attachment tongue of the core bar; and fastening means for securing the cap arrangement to the core bar, said means including a pair of wedges for insertion in respective ones of said wedge-receiving recesses, said wedges being formed for reaction against said foot, opposite ends of said cap arrangement, and the center-body, and means for forcing said wedges inwardly of said recesses.

6. In an impeller breaker, the combination with an elongate center-body having at least one re-entrant and longitudinally extending locking groove, and wedge-receiving recesses at opposite ends of said groove, of a composite impact bar assembly which comprises an elongate core bar having longitudinally-extending foot, cap-attachment portion, and intermediate web, said foot being shouldered longitudinally with respect to the web and secured within said re-entrant locking groove of said impeller center-body, and said cap-attachment portion being formed as a cross flange which projects outwardly from said locking groove as an attachment tongue for a cap arrangement, a wear and impact cap arrangement made up of a plurality of individual cap sections having their undersurfaces correspondingly re-entrantly grooved for snug mating with the attachment tongue of the core bar, said cap sections being mounted together in end-to-end lon-

11

itudinal alignment upon said attachment tongue of the core bar, and fastening means securing said cap arrangement to the core bar, said fastening means including a pair of wedges respectively formed for reaction against said foot, against the terminal sections of said cap arrangement, and against the center-body, said wedges being inserted in respective ones of said web-receiving recesses, means for forcing said wedges inwardly of said recesses, and a series of passages extending through underportions of the respective cap sections transversely of the length thereof and into the center-body, and fastening elements positioned within the respective passages.
